VAPORIZER

Application filed April 26, 1928. Serial No. 272,918.

This invention relates to mechanical refrigerating apparatus, and more particularly to vaporizers.

An object of my invention is to increase the efficiency of mechanical refrigerating systems by an improved vaporizer construction.

Another object of my invention is to provide a vaporizer with pipe loop extensions which are arranged so that a uniform and maximum heat exchange will be had through any portion thereof.

A further object of my invention is to provide a vaporizer construction which will occupy only a minor portion of the space in a chamber to be cooled and which contains a total heat transfer wall surface at least equal to the total wall area of the chamber.

Another object of my invention is to provide a novel type of vaporizer which is of particularly compact design.

Other objects of the invention, more or less ancillary or incidental to the foregoing, will appear from the following description in connection with the accompanying drawings.

In the drawings Fig. 1 is a perspective view of a cabinet having refrigerating apparatus incorporating my invention associated therewith;

Fig. 2 is an elevational view partially in section, illustrating the preferred embodiment of my invention;

Fig. 3 is an end view of the vaporizer associated with a wall of the cabinet;

Fig. 4 is a sectional view of the vaporizer taken on line IV-IV of Fig. 3;

Fig. 5 is a plan view of a modified form of the vaporizer;

Fig. 6 is an end elevational view of the same;

Fig. 7 is a plan view of another modified form of vaporizer incorporating my invention;

Fig. 8 is an end elevational view of the same.

Referring now to the drawings by characters of reference, 10 illustrates a food storage display case providing a compartment or chamber for the reception of food, or the like, which is to be maintained at a substantially low temperature by mechanical re-

frigerating apparatus. With the exception of the vaporizer, which forms the subject of this invention, any conventional type of mechanical refrigerating apparatus can be utilized and reference may be had to Patent No. 1,476,546 for a specific illustration and description of the compressor-condenser and control mechanism which can be associated with my invention. A compressor-condenser unit 11 is preferably arranged exteriorly of the display case, the compressor being driven by the electric motor 12 which is controlled by automatic switch mechanism contained within the casing 13, the condenser being of the water cooled type arranged above and surrounding the compressor.

The vaporizer 14, which forms the subject of this invention, is preferably of the flooded type and is adapted to contain a body of volatile liquid refrigerant, preferably sulphur dioxide, and oil which are partially mutually soluble, the oil being of less specific gravity than the refrigerant. The vaporizer consists, generally, of a container portion 15 and looped tube extensions 16, suitable means being associated with the system for automatically maintaining a substantially constant quantity of both refrigerant and of oil in the vaporizer, and such control means being preferably arranged within the container.

The container 15 is constructed of metal of a character through which heat can be readily transmitted, and is, preferably, cylindrical in form, and includes an integral wall 17 at one end and an apertured ring member 18 secured to the other end, the aperture in the ring member being closed by the detachable plate 19.

The means for controlling the quantity of refrigerant and oil in the container are preferably carried by the detachable closure plate 19 and are removable therewith, as a unit, from the container. The closure plate is provided with a refrigerant inlet passage 20 located centrally and adjacent the bottom thereof, and with the inner end of this passage is associated a valve stem 21 which is operated automatically by a float carrying arm 22 to which it is pivotally attached. The

float carrying arm is pivoted to a bracket 23 which is detachably secured by screws 24 to a boss protruding from the inner wall of the closure plate. A fitting 25 is secured to the exterior face of the closure plate so that it communicates with the passage 20, and a conduit 26 extends from the condenser outlet to the fitting for supplying liquefied refrigerant and oil to the vaporizer when the valve is open. An outlet passage 27 is formed through the closure plate, above the inlet passage, and receives one end of an outlet tube 28. The outlet tube projects inwardly of the container, entirely above the liquid level therein, the open inner end thereof being preferably in the vapor space and adjacent the top central portion of the container to receive the vaporized refrigerant at a point where there is the least liquid particles. A fitting 29 is secured to the outer face of the closure plate so that it communicates with the passage 27 and the tube 28, and a return conduit 30 extends from such fitting to the compressor. A baffle member 31 extending from the closure plate is arranged directly beneath the tube to subdue the agitation at the surface of the liquid therebelow caused by the incoming liquid entering the colder refrigerant in the container.

30 The liquid refrigerant and oil, in solution, passes from the inlet conduit into the container when the valve is open, due to pressure exerted by the compressor. The valve mechanism is mounted and adjusted to open when 35 the body of liquid within the vaporizer falls below a predetermined level and to close when such level is present, so that as the liquid refrigerant vaporizes the valve will intermittently open automatically and admit more 40 liquid from the feed conduit. A definite quantity of oil passes into the vaporizer with the refrigerant due to their solubility, and there will be two definite liquid layers formed in the container because the oil being of lower 45 specific gravity than the refrigerant will collect in the upper level when the refrigerant with which it is in solution vaporizes. The liquid below the horizontal plane indicated by 32 will consist of refrigerant and a quantity of oil which is mutually soluble therewith, while the liquid above the plane 32 will be principally oil with a small quantity of refrigerant in solution therewith.

I have found that with a liquid condition 55 of such character, wherein a layer of oil overlies the refrigerant, the efficiency of the apparatus is reduced because of the retarding effect of the oil layer upon the release of gasified refrigerant therebelow to the vapor space 60 thereabove. In other words, the layer of oil has sufficient viscosity to restrain the normal movement of gasified refrigerant from the body of liquid refrigerant to the vapor space above the liquid. If a considerable thickness 65 of oil layer is not maintained at the top of

the liquid in a vaporizer of the character illustrated, ebullition will throw liquid refrigerant particles into the vapor space and they will travel into the return conduit and vaporize therein causing frosting, and hence 70 it is desirable to maintain a substantial quantity of oil in the vaporizer even though it reduces the efficiency. Vaporizers of the type just referred to are constructed with pipe loops, or duct means, extending from the 75 liquid container, either with both ends in communication with the lower refrigerant body in the container, or with only one end communicating with the liquid refrigerant body and the other end communicating with the 80 vapor space well above the liquid level. With tube loops having both ends below the liquid level in the container, there is no definite path in which the refrigerant gasifying therein will escape, and as a matter of fact, I have 85 found that it escapes from both ends, and further, such escape is retarded by the oil layer in the container so that as a consequence there are spasmodic releases of the gasified refrigerant causing a reduced efficiency of the vaporizer and the system. With loops having one end communicating with the container well above the liquid level, the oil layer and the liquid layer will originally be in the same 90 respective planes as in the container, but as the liquid refrigerant vaporizes and escapes from the pipe loop the oil released from solution will accumulate with the original oil layer in the tube loop, thus increasing the 95 resistance to the passage of gasified refrigerant therethrough causing a gradually increasing amount of gasified refrigerant to return to the container through the inlet portion of the tube loop. Eventually the oil will 100 accumulate in the pipe loop to a degree such that gasified refrigerant will not penetrate the same, thus causing the refrigerant which vaporizes to return to the container through the inlet portion of the tube loop. Such conditions materially reduce the heat transfer 105 efficiency of the tube loop and the system.

In order, therefore, to provide an evaporator with duct extensions adapted to produce maximum heat transfer, I have formed and associated the loops 16 with a container in a novel manner. This result is promoted by arranging the lower inlet leg 16^a of the loops in a plane adjacent to but at least below the top of the refrigerant layer in the container, and by arranging the return leg 16^b of the loops in a plane adjacent the top level of and at least partially above the oil layer in the container. The open ends of the tube loops project through the end 17 of the container at such positions and are secured thereto in open communication with the interior of the container. The tubes are preferably formed of copper, or a similar material having rapid heat transfer qualities, the two legs 115 being preferably of uniform cross section and 120

substantially parallel and extending in a horizontal plane. The distance between the upper and lower legs is preferably as little as possible so that the resistance of forces

5 and pressure to flow from the lower legs to the upper legs will be minimum. It will be seen that the major portion of the duct in the upper legs of the pipe loops are above the liquid level in the pipe loops and the con-

10 tainer, and thus as the resistance is less in the upper legs than in the lower legs which contain liquid refrigerant and oil, the refrigerant vaporizing in the loops will travel in the path of least resistance which is through

15 the unrestricted duct in the upper leg to the vapor space in the container above the liquid level. Vaporization in the tubes results in violent ebullition therein, and because of the arrangement of the tube loops with the con-

20 tainer, a very rapid circuitous circulation of refrigerant will take place in the single direction of flow from the container through the lower legs of the loops and through the upper legs of the loops back into the container.

25 The vaporized refrigerant and liquid refrigerant particles will in this manner form a flowing stream which will sweep the entire inner wall of the leg of the pipe loops above the portions containing liquid refrigerant,

30 and thus a substantially uniform heat transfer results from any point of the pipe loops so that maximum heat transfer is provided. A further advantage of this arrangement of the loops with respect to the liquid level is

35 that when vaporization is not taking place the oil layer in the loops formed at the top portion of the bend in the loops will be positively moved into the container with a minimum degree of ebullition, and further after such oil layer is initially moved it will not

40 accumulate again while any material vaporization is in progress because of the circulation of the refrigerant in a definite direction through the pipe loops.

45 The pipe loops should be disposed in a substantially horizontal plane and relatively close together for two reasons. The return leg of the loops must be disposed at least partially above the level of the oil in the

50 container but sufficiently close thereto to prevent material opposition to the vomiting of oil and a small quantity of liquid refrigerant through the return leg of the loops with the gasified refrigerant. The inlet leg of

55 the pipe loops must be below the level of the refrigerant in the container but not sufficiently lower that any material pressure will be exerted upon the liquid in the lowermost portion thereof by the column of liquid above

60 it in the loop, as the rate of vaporization of the refrigerant decreases with an increase of pressure thereon.

65 Another feature of my invention resides in the particular location of the return tube 31 and the arrangement for returning suffi-

cient oil by gravity to maintain a substantially constant quantity of oil in the vaporizer, so that a minimum quantity of vaporizing refrigerant will contact with the return tube. The return tube is inclined slightly 70 downwardly toward the outlet end, and is arranged entirely above the liquid level when vaporization is not in progress. I provide the tube with an opening 40 which is located adjacent the closure plate 19, such opening being above the normal oil level. When vaporization takes place in the container, the liquid level approaches the passage 40, and any surplus oil above the predetermined desired quantity in the container will flow 75 through the passage and travel by gravity through the tube into the return conduit 30 leading back to the compressor. With the oil outlet arranged normally above the oil level, there will be less liquid refrigerant passing through the passage 40 thus reducing the quantity of liquid refrigerant vaporizing in the return conduit, so that frosting of the return conduit is substantially 80 eliminated due to this cause.

85 The circuitous movement of the refrigerant through the tubes normally causes intense agitation of the liquid in the container, and in order to subdue the same I have provided a baffle 41 which extends in a vertical plane transversely across the container. The baffle is bent outwardly at its periphery to form a flange which is soldered or welded to the wall of the container. A plurality of peripherally arranged openings 39 are 90 formed through the baffle to permit the passage of liquid and gas therethrough. This baffle is necessarily arranged intermediate the end wall 17 and the valve float, the location of the same being adjacent the end wall 17 regardless of the form of the refrigerant control.

95 In order to further increase the efficiency of the vaporizer, I provide a plurality of similar spaced heat conducting fins 42 which are designed to have a total surface area preferably greater than the area of the walls of the chamber to be refrigerated. The vaporizer, including the container, tubes and fins, is compact and occupies a minor portion of the space within the chamber which it refrigerates. The compactness and efficiency of a vaporizer are important factors in commercial requirements, and this vaporizer has such qualities. The fins are constructed to lend themselves to rapid and economical manufacture and assembly upon the pipe loops. Each fin 42 is formed of a sheet of cuprous material, or material having similar heat transfer characteristics, and is punched to provide flanges 43 each of which surround an aperture to receive a leg of the pipe loop 16. The flanges are formed to be arranged in intimate metallic contact with the legs of the pipe loops and can be 100

95

130

soldered, or fixed in any other manner therewith. The fins are assembled to extend in a vertical plane which is the same direction in which the air travels in its passage when 5 adjacent thereto or contacting therewith. By this arrangement a minimum resistance is offered by the finned tube loops of the vaporizer to the circulation of the air in the chamber being refrigerated, and in this respect efficiency is helped by not unduly retarding the speed of the air circulating by the vaporizer, which circulation in the structure shown in the drawings is induced solely by convection.

15 The fins are of a similar area in cross section to the container so that a similar general section of the vaporized results. The fins are preferably formed and associated with the pipe loops 16 so that any point on 20 the periphery of each loop is substantially the same distance from a portion of the pipe loops. Thus the heat transferred has substantially the same distance to travel from all 25 peripheral portions of the fins to the pipe loops, and this will result in a uniform transfer and maximum efficiency of the fins. With such character of fins contacting with loops of which all portions will transfer a uniform maximum amount of heat, it will be 30 seen that the air passing thereby will be maintained at a uniform temperature with a compact structure. Further, a compact vaporizer, occupying only a minor portion of the space in the chamber, is provided and the 35 heat transfer surface is of great enough total area to reduce the running time of the apparatus to a minimum for maintaining a predetermined temperature, and also, any degree above freezing can be maintained 40 therewith without abstracting moisture from the air in the chamber and collection of the same on the vaporizer so long as the temperature of the vaporizer is above the dew point corresponding to the relative humidity of the 45 air in the chamber. In addition to the advantage of not deteriorating the food by the abstraction of moisture, the vaporizer under the above mentioned temperature and humidity conditions has the advantage of not requiring defrosting and eliminates the necessity of providing means for collecting condensation.

50 The vaporizer is arranged within the display case 10 and is secured in desired position 55 in the chamber by supporting means associated with each end thereof. The means for supporting each end of the vaporizer are similar, and include a bar 44 fastened to the inner top wall of the casing by screws 45, a spacing collar 46 being provided intermediate the bar and the wall. Two bracket members 47 extend through apertures in the ends 60 of the bars and are threaded and positioned relative to the bar by nuts 48 and 49. The 65 lower end of the brackets are curved to en-

gage beneath the upper legs of the tube loops. By adjusting the nuts, the position or level of the vaporizer in the casing can be regulated.

In Figs. 5 and 6, I have illustrated a modified form of vaporizer incorporating my invention, however, in this instance the tube loops 50 extend from the side of the container 15 rather than from the end thereof as in the preferred form. In addition, there 75 are four tube loops illustrated and the fins 51 are assembled in two rows, each thermally contacting with two pipe loops. The end fins of each row are secured together by a connecting member 52 which lends rigidity 80 to the structure. In all other particulars this modified form of vaporizer corresponds to the first described form.

In Figs. 7 and 8, I have illustrated a second modified form of vaporizer which incorporates the principles of my invention. This vaporizer is similar to the preferred form except that a single tube loop 53 is employed, and smaller fins 54 are associated with the 90 tube loop.

Various changes can be made in the vaporizers described without departing from the spirit of my invention and the scope of what I claim.

95 I claim:

1. A refrigerant evaporating unit comprising a refrigerant receiving vessel, means associated with the vessel for maintaining a constant quantity of liquid therein, a heat exchange conduit communicating at one end with the interior of the vessel both above and below the liquid level therein, and means associated with the opposite end of the conduit for providing communication with the vessel below the liquid level therein.

100 2. A refrigerant evaporating unit comprising a refrigerant receiving vessel, means for maintaining a constant quantity of liquid in said vessel, a plurality of horizontally disposed conduits communicating at one end with said vessel both above and below the liquid level therein, and means for supplying liquid from the receptacle to the remote ends of the conduits.

105 3. A refrigerant evaporating unit comprising a refrigerant receiving vessel, means for maintaining a constant quantity of liquid in said vessel, a plurality of horizontally disposed conduits each communicating at one end with the receptacle both above and below the liquid level therein, heat exchanging fins arranged along said conduits in perpendicular relation thereto, and means associated with the opposite ends of the conduits for providing communication with said receptacle below the level of liquid therein.

110 4. A refrigerant evaporating unit comprising a refrigerant receptacle, a float arranged in said receptacle for actuating a valve to maintain a constant quantity of liquid there-

in, a plurality of loops of finned conduit associated with the receptacle for circulating liquid to and from the receptacle, and a baffle arranged between the float and the loops for maintaining a relatively static condition of the liquid in the receptacle.

5. A refrigerant evaporating unit comprising a horizontally disposed cylindrical refrigerant receiving vessel having a closed 10 end, a removable head for the opposite end, means associated with the head for admitting refrigerant to and withdrawing refrigerant from the vessel including means for maintaining a constant quantity of liquid within 15 in the vessel, a plurality of horizontally disposed conduit loops communicating with the vessel, said loops each having horizontally disposed parallel legs arranged one above another the upper leg of each loop communicating with the vessel both above and 20 below the liquid level therein, the lower leg of each loop communicating with the vessel below the liquid level therein, the corresponding leg of each loop being disposed in 25 spaced relation in the same horizontal plane, and heat absorbing fins arranged in parallel relation along said legs transversely intersecting the latter.

6. A refrigerant evaporating unit comprising 30 a refrigerant receiving vessel, means associated with the vessel for maintaining a constant quantity of liquid therein, a heat-exchange conduit communicating at one end with the interior of the vessel both above and 35 below the liquid level therein, means associated with the opposite end of the conduit for providing communication with the vessel below the liquid level therein, and a heat-exchanging fin associated with said conduit 40 in thermal contacting relation thereto.

7. A refrigerant evaporating unit comprising 45 a refrigerant receiving vessel, means associated with the vessel for maintaining a constant quantity of liquid therein, a heat-exchange conduit communicating at one end with the interior of the vessel both above and below the liquid level therein, means associated with the opposite end of the conduit for providing communication with the 50 vessel below the liquid level therein, and a heat-exchanging fin disposed in thermal contact with said conduit and extending in a plane transversely intersecting the latter.

In testimony whereof I have affixed my signature.

FREDERICK R. ERBACH.
